APPARATUS FOR USE IN APPLYING PRESSURE TO SHOE BOTTOMS

Robert N. Sandberg, Beverly, Mass., assignor to
United Shoe Machinery Corporation, Paterson,
N. J., a corporation of New Jersey

Application May 26, 1934, Serial No. 727,769

39 Claims. (Cl. 12—33)

This invention relates to improvements in machines for applying pressure to shoe bottoms and is herein illustrated as embodied in a machine for cement-attaching soles to shoes, as for example, in the manufacture of compo shoes.

It is an object of the invention to provide improved means for positioning a shoe and sole relatively to each other before pressure is applied thereto, for example, as a preliminary to the application of sole-attaching or sole-laying pressure.

In accordance with the foregoing, a feature of the invention comprises an improved structure in which a pair of sole-positioning fingers or gages and a separate pair of shoe-positioning fingers are mounted on a pad box with which they are to cooperate. As illustrated herein the sole and shoe-positioning fingers are carried by a plurality of members located normally in a substantially horizontal position so that the ends of the sole-engaging fingers will just clear the sole-receiving surface of a pad in the pad box. Means is provided for adjusting the fingers or gages lengthwise of the pad to position them properly for operating upon shoes of different sizes and, in accordance with another feature of the invention, further means is provided for lifting the forward ends of the fingers away from the surface of the pad during their lengthwise movement and for returning them to their former positions at the end of such movement.

In accordance with still another feature of the invention the sole-positioning gages and the shoe-positioning gages are fulcrumed for rocking movement in equal amounts but in opposite directions about axes alined with each other transversely of the pad. As illustrated, both sets of gages are operated respectively by slide members mounted for movement transversely or widthwise of the pad box, said members being provided with cam surfaces arranged to engage cooperating portions of the respective pairs of gages so that movement of the slides transversely of the pad box moves the gages of the two pairs toward or from each other, thereby causing the sole-positioning gages to position a sole relatively to the pad in the pad box and, subsequently, causing the shoe-positioning gages to position a shoe relatively to the previously positioned sole.

In accordance with still another feature of the invention the shoe gages of the illustrated construction are carried by a slide member which is mounted for adjustment relatively to the sole gages transversely of the pad so that the shoe gages may be moved bodily relatively to the sole

gage whatever amounts may be necessary to compensate for a lack of symmetry in that portion of the shoe engaged by the shoe gages or in the desired location of the shoe with respect to the sole.

The above and other objects and features of the invention including a novel arrangement for obtaining additional space between the ends of the sole-engaging fingers and the shoe-engaging fingers when operating upon shoes having relatively high heels will now be described in connection with the accompanying drawings and pointed out in the appended claims.

In the drawings,

Fig. 1 is a front elevation of a pad box embodying my invention illustrating also mechanism for positioning the foreparts of a sole and shoe relatively to each other on the pad of the pad box, and a part of the pressure-applying mechanism of a cement sole-attaching machine;

Fig. 2 is a sectional view of the rear or heel portion of the pad box shown in Fig. 1 taken on the longitudinal center line of the pad box;

Fig. 3 is a plan view of the heel portion of the

pad box and the gage mechanism for positioning the heel ends of a sole and shoe relatively to

each other on the pad;

Fig. 4 is a sectional view of the gage mechanism taken on the line IV—IV of Fig. 3;

Fig. 5 is a perspective view partly in section showing in more detail the fingers of the gage mechanism which position the heel end of the sole upon the pad, together with portions of the mechanism for operating such fingers;

Fig. 6 is a detailed view in side elevation of a portion of the connections carried by the pressure-applying mechanism shown in Fig. 1 for operating the shoe-positioning gages; and

Fig. 7 illustrates a portion of the operating connections for the shoe-positioning gages.

The invention is illustrated herein as embodied in a pad box for use in a cement sole-attaching machine of the type disclosed in an application for Letters Patent of the United States Serial No. 636,202, filed October 4, 1932, in the name of Milton H. Ballard et al. The pad box B (Fig. 1) comprises a stationary casting 10 secured by screws 12 to a forwardly extending portion of a shelf or bracket 14 which projects radially of the rotary turret of the machine. The casting 10 carries at its forward or left hand end, as viewed in Fig. 1, a movable casting 16 arranged for pivotal movement about a virtual axis located in a plane coinciding substantially with the sole-engaging surface of a fluid-filled pad P mounted

in the pad box. The casting 16 is provided with a mask plate 18 movable longitudinally of the pad and carrying a plurality of sole and shoe-engaging fingers or feelers arranged respectively to find the edge faces of the forepart of a sole placed on the pad by an operator and to locate a shoe relatively to the sole.

The above mechanism forms no part of the present invention and accordingly is not described in further detail herein. It is however, fully disclosed and claimed in an application for Letters Patent of the United States Serial No. 724,546, filed May 8, 1934, in the names of Kennison and O'Brien.

15 On its rear or right-hand end, as viewed in Fig. 1, the casting 10 is provided at each side with vertical surfaces 20 which assist in positioning transversely of the casting 10 a substantially horizontal bracket 22 slidably mounted on the casting. The bracket 22 is supported on the casting 10 by a pair of interconnected bell crank levers 24, 26 formed on the opposite ends of a cross piece 28 (Fig. 2) extending transversely of the bracket and loosely surrounding a horizontal shaft 30 mounted in a pair of downwardly projecting ears 32 formed on the lower portion of the bracket. The bell crank levers 24, 26 are pivotally mounted on a fixed shaft 34 extending transversely between the opposite side walls 30 of the main casting 10 and the levers are provided with upwardly extending arms 36, 38, the upper ends of which are connected by means of a pair of heavy tension springs 40, 42 to another fixed shaft 44 mounted in the casting 10 forwardly of the shaft 34. The springs 40, 42 tend to urge the bell crank levers about the pivot 34 in a counterclockwise direction, as viewed in Figs. 1 and 2, to maintain the bracket 22 in its uppermost position on the casting 10.

40 The upper portion of the movable bracket 22 is held on the guideways 20 by a pair of substantially horizontal links 46, 48 pivotally connected to the opposite side walls of the casting 10 by short horizontal pins 50, and pivotally connected to the movable bracket 22 by similar pins 52 these links, together with the interconnected bell crank levers 24, 26, forming in effect a parallel motion arrangement whereby the bracket 22 will move on the guideways in a substantially vertical direction.

55 The stationary casting 10 has an upstanding wall 54 (Fig. 2) located near its right-hand end and at the upper end of this wall is formed a horizontal shelf 56 which projects rearwardly and has an upper surface which supports the rear end of the pad P. Mounted on the movable bracket 22, a short distance below the shelf 56, is another shaft 58 which extends transversely of the bracket 22 and, near its forward end as viewed in Fig. 2, carries a cam 60 (shown in broken lines in Fig. 2), which engages the under side of the shelf 56 and thereby determines the heightwise position of the movable bracket 22 relatively to the casting 10 and the pad P. The shaft 58 is rotated to change the position of the cam 60 and thus vary the heightwise position of the bracket 22 relatively to the pad by means of a hand wheel 62 (Fig. 1) secured to the forward end of the shaft 58, the hand wheel, as shown in Fig. 1, being provided at its periphery with numerals to indicate the position of the cam 60 with respect to the horizontal wall 56. In Fig. 2 the cam is shown with its high part contacting 70 with the lower surface of the shelf 56 so that the

bracket 22 is located in its lowest position relatively to the main casting 10.

The opposite side walls of the bracket 22 extend upwardly for some distance at the forward portion of the bracket and at their upper ends are connected by a horizontal wall 64. Secured to the rear portion of the under surface of this wall 64 is a tongue 66 the lower portion of which is provided with laterally projecting flanges which support a pair of slotted plates 68 arranged for sliding movement on the tongue. The rear portion of the pad P, as shown in Fig. 2, is provided with a horizontal groove or recess in which is located the horizontal wall 64, the portion of the pad above the recess forming a flap 70 which rests on the wall 64. When the bracket 22 is moved upwardly on the casting 10 by adjustment of the cam 60 and the action of the tension springs 40, 42, the rearwardly extending flap 70 is moved upwardly away from an underlying fluid-filled portion of the pad, thus providing additional space into which the slide plates 68 may be moved. The underlying portion of the pad is covered by an angular plate 72, held in position by a transverse pin 74, to prevent this portion of the pad from bulging excessively when a shoe is pressed thereon. The above mechanism, the purpose of which is to enable the pad P to accommodate shoes having heels of different heights, and the means for operating this mechanism, form no part of the present invention and accordingly are not described in further detail herein. These mechanisms are, however, fully described and claimed in an application for Letters Patent of the United States Serial No. 722,537, filed April 26, 1934, in the name of Frank Kennison.

55 The movable bracket 22 also carries mechanism for positioning the heel portions of a sole and shoe relatively to each other on the pad P. 40 This mechanism comprises a pair of sole-engaging fingers 76, 77, best shown in Figs. 1 and 5, and a pair of shoe-engaging fingers 78, 79, the two fingers of the respective pairs being connected by intermeshing gearing 80 and 82, as shown in 45 Figs. 3, 4 and 5. These two sets of fingers are carried by a group of three approximately horizontal castings 84, 86 and 88 (Figs. 1 and 2) secured one upon another by cap screws 90, the lower casting 84 being pivotally connected by a 50 pin 92 mounted transversely in the casting 84 to the upper ends of a pair of upwardly projecting arms 94, 95 of a yoked lever 96 which, in turn, is pivoted on a transverse shaft 98 mounted in the opposite side walls of the bracket 22. The 55 opposite ends of the pivot pin 92, which engage the upstanding arms 94, 95, are reduced in size and are located eccentrically with respect to the main portion of the pin which is housed in the casting 84. The forward end of the pin, as viewed in Fig. 1, projects beyond the arm 94 and is provided with an enlarged portion 100 whereby the pin may be rotated by hand in the casting 84. Rotation of the pin 92 changes the position of the group of castings with respect to the upper 60 ends of the arms 94, 95 of the yoked lever 96 and provides a means of obtaining a quick adjustment of the castings and the gages carried thereby relatively to the movable bracket 22. As shown in Fig. 2, the pivot pin 92 is held in either one of 70 two positions by means of a plunger 102 mounted in a hole in the casting 84 and urged toward the pivot pin by a compression spring 104 which forces the end of the plunger into depressions 106, 107 formed in opposite sides of the pin 92, thus 75

preventing the pin from turning accidentally. The rear end of the lower casting 84 is provided with a downwardly and rearwardly projecting lug 108, the lower portion of which has ears formed thereon (Fig. 3) between which is mounted, on a transverse pin 110, a roll 112. The roll 112 engages a convex surface 113 formed on the head of a stud 114 mounted for vertical adjustment in a boss 115 formed at the rear end of the bracket 22, the roll being held in engagement with the convex surface of the stud by a tension spring 116 connected at one end to the pin 110 and at its other end to a pin 118 mounted in the side of the boss. The stud 114 is adjusted by means of an adjusting screw 120 threaded into the lower portion of the boss 115, the upper end of the screw contacting with the lower end of the stud, as shown in Fig. 2. Adjustment of the screw 120 in the boss 115 will, of course, raise or lower the stud a corresponding amount. The screw is held in adjusted position by a lock nut 122 threaded on the screw and engaging the lower surface of the boss.

It will be seen from an examination of Figs. 1 and 2, that the group of castings which carry the sole and shoe-positioning fingers or gages are normally supported in a substantially horizontal position and the construction of the fingers is such that, with the castings located in this position, the sole-positioning fingers 76, 77 will just clear the upper surface of the pad P. The group of castings 84, 86 and 88, and the sole and shoe-positioning gages may, however, be adjusted out of a horizontal plane if necessary or desirable by heightwise adjustment of the vertical stud 114 which will rotate the casting 84 about the pivot 92 to raise or lower the ends of the gages until there is just the right amount of clearance between the lower or sole-engaging fingers and the surface of the pad to accommodate the particular type of shoe to be operated upon.

The pad box is adapted to operate upon shoes having relatively flat soles and also upon shoes which are to take relatively high heels, for example, shoes having considerable spring at the shank portions so that the heel seat portions of such shoes are elevated relatively to the foreparts, as in the larger sizes of misses' shoes and in women's shoes. In these latter types of shoes, because of the higher position of the heel-seat portion relatively to the forepart, it is sometimes necessary to utilize an auxiliary pad comprising a layer of rubber arranged to cover only the heel portion of the pad P and having openings at each side which fit over projections or pins (not shown) formed on the opposite side walls of the movable bracket 22. This auxiliary pad is usually from a quarter of an inch to three-eighths of an inch in thickness, although it may be made thicker if necessary or desirable, and it serves to raise the heel portion of the pad high enough to cause it to contact with the heel-seat portion of the bottom of a shoe which is arched as described in the shank portion and is to take a relatively high heel. The adjustment provided by the eccentric pivot pin 92 permits a quick adjustment of the forward ends of the gages relatively to the upper surface of the auxiliary pad referred to when operating successively upon shoes which are to have relatively high heels and when operating upon shoes which have substantially flat soles where the auxiliary pad is not necessary.

The yoked lever 96 has a downwardly extending arm 126 at its forward end, as viewed in Fig. 1,

which carries at its lower extremity a spring-pressed pin 128 provided with a handle 130 and urged inwardly of the arm 126 toward the bracket 22 by means of a compression spring 132 surrounding the pin 128 and having its forward end bearing against an enlarged head on the pin and its rear end bearing against a solid portion of the arm 126. The forward end of the pin 128 is arranged to fit into either one of two holes 134, 136 formed in the forward side wall of the bracket 22 to hold the lever 96 either in a rearwardly inclined position, as shown in Figs. 1 and 2, or in a forwardly inclined position. In this way the castings 84, 86, and 88, and the sole and shoe-positioning gages carried thereby, may be adjusted longitudinally or lengthwise of the pad a predetermined amount to position the gages properly for operating upon shoes of different sizes. A pair of small pins 138, 140 located respectively at opposite sides of the holes 134, 136 prevent the lever 96 from passing beyond the positions in which the spring-pressed pin 128 registers with the holes 134, 136.

In order to prevent the sole-positioning gages 76, 77 from scraping across the upper surface of the pad during the lengthwise adjustment, the convex surface 113 of the vertical stud 114 is shaped so that it will cause the castings 84, 86 and 88 to be tipped slightly in a clockwise direction about the pivot 92 as the yoked lever 96 is moved from the position shown in Figs. 1 and 2 to the position that it occupies when the plunger 128 is located in the hole 136. As the roll 112 rides over the high portion of the convex surface 113 and starts down the inclined portion, the castings will rock slightly about the pivot pin 92 in an opposite or counterclockwise direction to lower the sole gages again into close proximity to the upper surface of the pad as the pin 128 snaps into the hole 136 in the bracket 22. Consequently, the gages, while being maintained normally by the castings 84, 86, and 88 in a substantially horizontal plane in either position of adjustment, are raised slightly from the upper surface of the pad during their longitudinal adjustment thereby preventing the sole-engaging fingers from scraping across the surface of the pad.

When the sole-attaching pressure is applied the sole of the shoe will sink somewhat into the fluid-filled pad P and, since the heel portion or flap 78 of the pad is supported by the horizontal wall 64 of the bracket 22, this bracket is pressed downwardly on the guideways 29, this action being permitted by the tension springs 40, 42 which support the bracket in its uppermost position as determined by the cam 60 and the horizontal wall 58. Consequently, the relation of the shoe and sole-positioning gages to the shoe and sole during the pressure-applying operation is not disturbed, the gages being mounted on the bracket 22 moving downwardly therewith and thus being prevented from rubbing against the shoe upper or across the edge faces of the sole on the pad.

The sole-engaging fingers 76, 77 are pivoted at 142 and 144 to the casting 86 as shown in Fig. 4. An extension of the finger 77 carries beneath its lower surface a roll 146 (Figs. 4 and 5) located in an inclined cam slot 148 formed in a slide member 150 mounted for forward and rearward movement, that is, movement toward and away from the operator and therefore widthwise or transversely of the pad box. Thus, movement of the slide 150 will rock the

5 fingers 76, 77 about their pivots 142, 144. The slide member 150 is in its operative position when it is at its extreme rearward position transversely of the pad box so that the roll 146, as shown in Fig. 4, is located at the forward end of the inclined slot 148. The slide is held in this rearward position by means of a compression spring 152 housed in a lower portion of the casting 88 and bearing at one end against the casting and at the other end against a downwardly projecting portion 154 of the slide 150. In this position, therefore, the sole-engaging ends of the fingers 76, 77 have been swung toward each other into engagement with the edge faces of a sole 15 S (Fig. 3) mounted by the operator on the pad. When the pad is at the operating station, however, before the sole-attaching pressure is applied, the spring 152 is held under compression with the slide 150 in its forward position so that 20 the fingers 76, 77 are positioned with their sole-engaging ends separated.

10 The mechanism which compresses the spring and moves the slide forwardly to separate the fingers comprises a bell crank lever 156 (Fig. 3) 25 mounted on a pin 157 carried by a rearwardly projecting portion 158 of the movable bracket 22. The bell crank lever 156 has a rearwardly projecting arm which carries a roll 160 arranged to engage the downwardly projecting portion 30 154 of the slide member 150. The lever 156 has a forwardly extending arm connected by a link 162 to the upper portion of an upwardly extending arm of another bell crank lever 164 (Fig. 7) 35 which forms a part of the mechanism which connects the bell crank lever 156 to treadle mechanism through which the lever 156 is operated, this mechanism being described more fully hereinafter. When the treadle of the machine is depressed the bell crank lever 156 moves 40 about the pivot 157 in a counterclockwise direction to withdraw the roll 160 to the position shown in Fig. 3, thereby allowing the compression spring 152 to expand to force the slide 150 rearwardly and move the sole-engaging ends 45 of the gage fingers 76, 77 toward each other and into engagement with the sole on the pad. Later in the operation of the machine, after the shoe and sole have been positioned on the pad, the roll 160 is moved forwardly to engage the slide 50 150 and force it forwardly to withdraw the gage fingers from engagement with the sole.

55 The shoe-engaging fingers 78, 79 are located approximately above the sole-engaging fingers 76, 77 and are provided with gear segments intermeshing at 82 to maintain the fingers properly centralized. These shoe-engaging fingers are pivoted at 166, 168 (Fig. 4) to a slide 170 normally secured to the casting 88 by a friction clamp arrangement comprising an adjusting lever 172, by the adjustment of which (as hereinafter more fully explained) the center line with respect to which the shoe-engaging fingers are centralized, may be adjusted transversely of the pad relatively to the line with respect to 60 which the sole-engaging fingers 76, 77 are centralized, thus compensating for the unsymmetrical shape of the heel portion of a shoe whenever such condition exists. The shoe-engaging finger 79 is provided on its upper surface with a roll 174 (Figs. 3 and 4) located in an inclined cam slot 176 formed in another slide member 178 mounted for forward and rearward movement in the casting 88. The slide 178 has secured to its upper surface an upwardly extending bracket 180 to which is connected by a ball 65

70 and socket joint 182 a rearwardly extending link 184 as shown in Figs. 3 and 4. The link 184 is pivoted at 186 (Figs. 3 and 6) to an arm 188 which in turn is pivoted at 190 to a forwardly and rearwardly swinging frame member 192 which forms a part of the machine disclosed in application Serial No. 636,202, mentioned above, the swinging frame, when pressure is to be applied to the sole and shoe on the pad, being swung forwardly, as viewed in Figs. 1 and 3, by 10 means of a handle 194 grasped by the operator.

15 In Fig. 6 the swinging frame 192 has been moved out of the substantially vertical or pressure-applying position shown in Fig. 1 into its inoperative or rearward position. The arm 188 which, in the pressure-applying position of the swinging frame, is rotated to the right of the position shown in Fig. 6 has, during the rearward movement of the swinging frame, been rotated in a clockwise direction or toward the left until it 20 becomes latched to the swinging frame member 192, as illustrated in Fig. 6. For this purpose a latch lever 198 is pivoted at 200 to the swinging frame 192 and is urged in a counterclockwise direction by a tension spring 202 secured at one end 25 to the lever 198 and at the other end to a portion of the swinging frame. The other end of the latch lever 198 is provided with an angular detent 204, preferably a block of hardened metal, arranged to be received in a notch 206 formed in 30 a rearwardly projecting lug 197 of the arm 188. An adjustable screw 207, threaded into a projection on the latch lever 198 and arranged to engage the swinging frame 192, serves to limit 35 counterclockwise movement of this lever relatively to the swinging frame. Thus when the swinging frame 192 is moved forwardly by the operator from the position shown in Fig. 6 to the pressure-applying position shown in Fig. 1 with the arm 188 latched to the swinging frame, the shoe-engaging fingers 78, 79 are, by forward movement of the transverse slide 178, moved toward each other until they engage the opposite sides of the shoe, which has been placed on the sole S, and 40 position or centralize the shoe with respect to the sole. After the shoe has been centralized, the resistance to further forward movement of the connecting rod 184 is sufficient to force the notch 206 rearwardly over the end of the detent 204, thereby releasing the latch mechanism, as shown 45 in Fig. 1, and permitting the swinging frame 192 to be pulled further forwardly into pressure-applying position without causing the shoe-engaging fingers to exert undue pressure on the shoe. 50

55 After the latch mechanism is released and the link 184 is disconnected from the swinging frame 192, the shoe-engaging fingers are held against the shoe only by the slide 178. While the fingers cannot be forced away from engagement with the shoe because of the angle of inclination of 60 the slot 176 in which the roll 174 is located, this angle being such that the fingers are locked against opening movement, nevertheless, if there should be some slight movement of the shoe relatively to the sole, for example, if the shoe should move forwardly slightly relatively to the sole before the pressure is actually applied, the swinging frame cannot now move the slide further forwardly to cause the fingers to be moved further inwardly into engagement with the shoe. In order, therefore, to keep the fingers bearing against the sides of the shoe even if there is some slight movement of the shoe relatively to the sole after the latch mechanism has been released 65 but before pressure is applied to the shoe and sole, 70

a tension spring 208 (Figs. 2 and 3) is provided. The tension spring is secured at one end to the rear end of the slide 178 and at the other end to the casting 86 and tends to urge the slide forwardly to force both fingers lightly against the sides of the shoe.

The swinging frame 192 is provided with suitable means for pressing the sole and shoe against the pad P, this means comprising a pair of last and shoe-engaging abutments 210 and 212 (Fig. 1) arranged respectively to engage the last in the shoe being operated upon and the forepart of the shoe. The abutments are forced downwardly to apply the sole-attaching pressure by mechanism which may be of the character disclosed in the Ballard et al. application Serial No. 636,202 mentioned above.

The shoe-engaging fingers 18 and 19 are withdrawn from the shoe after they have centralized the shoe with respect to the sole and the pressure has been applied in the following manner. When the pad reaches the station of the machine just ahead of the operating station, the pressure on the shoe and sole is released thus allowing the swinging frame to be swung out of position over the shoe and moved rearwardly into inoperative position, this being done by mechanism which is described in the Ballard et al. application previously referred to. As the swinging frame swings rearwardly to inoperative position the tension spring 208 operates to hold the slide 178 forwardly and thus keeps the shoe-engaging fingers against the shoe until the arm 188 on the swinging frame is moved forwardly or, as viewed in Fig. 6, toward the left and the notch 206 thereon rides over and engages the detent 204 on the latch lever 198, which, through the link 184, again connects the slide member 178 to the swinging frame 192. Further rearward movement of the swinging frame carries the slide 178 rearwardly against the tension of the spring 208 and thus moves the shoe gages into their open or inoperative positions.

The outer ends of the sole-engaging fingers 16, 17, as shown in Fig. 1, curve downwardly toward the pad and the arrangement is such that the fingers just clear the upper surface of the pad when the latter is in an idle or inoperative position. The outer ends of the shoe-positioning fingers 18, 19 are provided with shoe-engaging devices comprising a pair of elongated plates 214, 216 which are mounted in vertical slots (Fig. 3) formed in the outer ends of the fingers and are held in the slots by means of compression springs 218, 220, each of which bears at one end against the bottom of an opening in the end of its corresponding finger and, at its other end, against a washer mounted on the shank portion of the plate on such finger. By this arrangement the elongated plates may be positioned, as shown in Fig. 1, with the elongated portion projecting upwardly or, by pulling the plates out of the vertical slots against the action of the compression springs, the plates may be reversed so that the extended portions will project downwardly toward the sole-positioning fingers. This adjustment of the plates on the shoe-positioning fingers permits the fingers to operate upon shoes having relatively flat heel portions or upon shoes such as youths' and misses' shoes, which are sometimes provided with wedge or spring heels, the wedges which form these heels being usually inserted between a relatively thin sole and the bottom of the shoe, as shown at W in Fig. 2.

The mechanism for adjusting the transverse slide 178 relatively to the casting 86 is illustrated

best in Figs. 4 and 5. As shown in Fig. 5, the slide 178 is provided with a T-shaped slot 222 and the casting 86 is provided with a slot 224 (shown dotted in Fig. 5) underlying the bar portion of the T-shaped slot 222 and somewhat greater in length than the bar of this T slot. A block 226 is secured to the casting 86 by a screw and slot connection 228 and the block 226 is provided with a tapered hole 230 (Fig. 4) serving as a seat for the hub portion 232 of the adjusting lever 172 mentioned above. A crank pin 234 (Fig. 3) projects from the hub 232 into the upright portion of the T-shaped slot 222 so that when the lever 172 is rotated the slide 178 will be moved lengthwise relatively to the casting 86. In order to prevent the lever 172 from escaping, the shank of a screw 236 passes through a hole bored in the hub 232 and through the slot 224, the screw being provided at its lower end with a nut 238 bearing against a plate 240 (Fig. 4) underlying the casting 86. To provide suitable friction so that the slide 178 will remain in adjusted position a spring 242 surrounding the shank of the screw 236 is housed in the hub 232, the lower end of the spring bearing against a flange formed on the bottom of the hub and the upper end bearing against a washer underlying the head of the screw 236. By means of this construction it will be seen that the friction between the slide 178 and the casting 86 may be adjusted by turning the screw 236 more or less through the nut 238, thereby compressing the spring 242 to a greater or less extent.

The operation of the sole-positioning gages 76, 77 is accomplished in the following manner. The bell crank lever 156, counterclockwise movement of which (as viewed in Fig. 3) permits the compression spring 152 to move the slide 150 rearwardly and thus move the sole gages into operative position, is operated, when the pad box 40 is at the operating situation of the machine, by depression of a foot treadle 244 (Fig. 7). As already pointed out, the left-hand end of the link 162 is connected at 246 to the upper end of the bell crank lever 164. The lever 164 is fulcrumed at 248 to a suitable part of the rotary frame or turret of the machine. A tension spring 250, anchored at 252 to the upstanding arm of the bell crank lever 164 and at 254 to the frame of the machine, urges the lever 164 in a clockwise direction or toward the right, as viewed in Fig. 7, this movement being limited by an adjustable stop 256 which engages a stationary abutment 258 on the turret. Thus, the spring 250 tends to retract the roll 160 on the bell crank lever 156 from engagement with the transverse slide member 150.

A rod 260 extends upwardly from the treadle 244 forwardly of the fulcrum thereof and is pivoted at 262 to a lever 264 which is fulcrumed at 266 to a stationary cam track 268 adjacent to the operating station of the machine and in close proximity to the path of movement of an approximately horizontal arm 270 of the bell crank lever 164 as the pad moves into and away from the operating station. A roll 272 carried by the horizontal arm 270 rides upon the stationary cam track 268 as the pad nears the operating station, rocking the lever 164 in a counterclockwise direction, as viewed in Fig. 7, and thereby rocking the bell crank lever 156 in a clockwise direction, as viewed in Fig. 3, to move the slide 150 forwardly or toward the operator thereby separating the sole-engaging fingers 16, 17 and moving them out of operative position. A movable cam track 75

section 274 carried by the lever 264 forms a continuation of the cam track 268 and is so positioned that the rotary turret of the machine comes to rest with the roll 272 of the appropriate bell crank lever 164 resting on the movable cam track section 274. With the parts in this position, the bell crank lever 164 has been rocked in a counter-clockwise direction from the position shown in Fig. 7 so that the roll 160 carried by the bell crank lever 156 has been moved to force the slide 150 forwardly and thus withdraw the sole-engaging fingers 16, 17 from engagement with the sole.

After the shoe previously operated upon has been removed from the pad and a suitably prepared sole has been placed thereon with its heel portion between the gage fingers 16, 17, the operator depresses the treadle 244 thereby moving the cam track section 274 of the lever 264 downwardly. This permits the bell crank lever 164 to rock 20 in a clockwise direction to the position shown in Fig. 7 under the action of the tension spring 250, thereby rocking the bell crank lever 156 (Fig. 3) in a counterclockwise direction to permit the compression spring 152 to expand and thus urge the sole-engaging fingers 16, 17 into engagement with the sole on the pad. In order that it will not be necessary for the operator to retain his foot upon the treadle 244, a latch lever 276 is fulcrumed at 278 to the stationary cam track 268. 25 The latch lever 276 is provided with a shoulder 280 engaging a hardened steel plate 282 secured to the lever 264 and is urged in a counterclockwise direction, as viewed in Fig. 7, by a tension spring 284 connected at its other end to the stationary cam track 268. Thus, when the treadle 244 is depressed to lower the lever 264, the latch lever 276 on the stationary cam track is moved by the spring 284 until its shoulder 280 snaps over the end of the plate 282 thereby latching the lever 40 264 in the lowered position shown in Fig. 7. The operator may now remove his foot from the treadle 244.

After a shoe has been positioned upon the sole on the pad and the sole-attaching pressure has 45 been applied, the turret rotating mechanism is operated, as described in the Ballard et al. application Serial No. 636,202, and the bell crank lever 164 moves bodily to the right, as viewed in Fig. 7. In order to release the shoulder 280 of the latch 50 276 and permit the lever 264 to rise, a cam roll 286 is carried by the bell crank lever 164, the axis of the roll 286 coinciding with the axis about which the bell crank lever 164 is fulcrumed. The upper side of the lever 264 has at its right-hand 55 portion, as viewed in Fig. 7, a convex surface 271 formed thereon, this surface being inclined upwardly for about half its length and then extending downwardly to the end of the lever. As the roll 286 moves to the right, it first engages the inclined surface 271 on the lever 264, depressing that lever slightly and thereby relieving the pressure of the plate 282 against the shoulder 280, after which the roll 286, without releasing the lever 264, contacts with an upwardly extending 60 cam surface 288 formed on a finger extending to the right from the latch lever 276, thereby rocking this lever in a clockwise direction against the tension of the spring 284 to unlatch it from the plate 282 and, since the roll 286 has not yet passed 65 out of engagement with the inclined surface 271 on the lever 264, permitting this lever to rise gradually under the action of a treadle spring 294, thus preventing the treadle 244 from being returned to its inoperative position too suddenly by the 70 spring 294.

The lower end of the rod 260 is surrounded by a compression spring 290 bearing at its upper end against an abutment 292 and at its lower end against a suitable surface formed on the treadle 244. The lower end of the rod 260 passes through a hole in a suitable part of the treadle and is provided with an enlarged collar or nut so that positive depression of the rod 260 by the roll 286 does not positively depress the treadle 244 but acts upon it through the spring 290. The treadle is 10 held normally in an elevated position by the spring 294 which is secured at its lower end to a suitable portion of the treadle and at its upper end to a lug on a stationary portion of the frame of the machine. The spring 290 provides a safety 15 device which permits the treadle to stop in its downward movement if the operator's foot or other object should happen to be under the treadle as the latter is being forced downwardly by the rod 260. 20

Having described my invention, what I claim as new and desire to secure by Letters Patent of the United States is:

1. A pad box for use in applying pressure to shoe bottoms provided with a sole-receiving pad, 25 a pair of relatively movable sole-positioning gages carried by the pad box, and a separate pair of shoe-positioning gages also carried by the pad box and constructed and arranged to position a shoe relatively to a sole positioned on the pad by the 30 sole positioning gages.

2. A pad box for use in applying pressure to shoe bottoms provided with a sole-receiving pad, and means for positioning an end portion of a shoe and sole on the pad comprising a pair of 35 sole-engaging fingers and a separate pair of shoe-engaging fingers, both said pairs of fingers being carried by a bracket adjustably secured to the pad box.

3. A machine for applying pressure to shoe bot- 40 toms having, in combination, a pad box comprising a pad constructed and arranged to receive a sole and shoe, means movable into position over the pad and cooperating therewith to apply pressure to a shoe and sole positioned on the pad, a 45 pair of gage members carried by the pad box and movable into engagement with the opposite edges of the sole of a shoe on the pad thereby to position the sole relatively to the pad, and a pair of gages movable toward and from each other to position 50 a shoe relatively to the sole which has been positioned on the pad.

4. A machine for applying pressure to shoe bottoms having, in combination, a pad to receive a sole and shoe, means movable into position over 55 the pad and cooperating therewith to apply pressure to a shoe and sole positioned on the pad, a pair of gage members movable toward and from each other, treadle controlled mechanism constructed and arranged to move the gage members 60 into engagement with the opposite edges of the sole of a shoe on the pad thereby to position the sole relatively to the pad, a second pair of gage fingers movable toward and from each other to position 65 a shoe relatively to the sole which has been positioned on the pad, and connections controlled by the movement of the pressure applying means into operative position to operate the shoe positioning gages thereby to position the shoe 70 relatively to the sole.

5. A machine for applying pressure to shoe bottoms having, in combination, a sole and shoe receiving pad, an upwardly extending pivotally mounted frame adjacent to the pad, means carried by said frame and movable into operative posi- 75

tion by forward swinging movement of the frame to engage a shoe on the pad and thereafter to apply pressure to the shoe, a pair of gages adjacent to the pad mounted for movement toward and from each other to position a shoe on the pad, and connections between the swinging frame and the gages such that forward swinging movement of the frame brings the gages into engagement with the shoe, thereby positioning the shoe on the pad.

6. A machine for applying pressure to shoe bottoms having, in combination, a sole and shoe receiving pad, an upwardly extending pivotally mounted frame adjacent to the pad, means carried by said frame and movable into operative position by forward swinging movement of the frame to engage a shoe on the pad and thereafter to apply pressure to the shoe, a pair of gages adjacent to the pad mounted for movement toward and from each other to position a shoe on the pad, and connections between the swinging frame and the gages such that forward swinging movement of the frame brings the gages into engagement with the shoe, thereby positioning the shoe on the pad, said connections including latch mechanism responsive to pressure and constructed and arranged to disconnect the connection between the frame and gages when the gages have been brought into contact with the shoe on the pad.

7. A machine for applying pressure to shoe bottoms having, in combination, a sole-engaging pad, a shoe-engaging device movable into position over the pad and constructed and arranged to cooperate with the pad in applying pressure to a shoe and sole on the pad, a pair of gages for positioning the heel-end portion of a sole on the pad, a second pair of gages for positioning the rear end of a shoe relatively to said sole, and connections operated by the movement of said shoe-engaging device into position over the pad for operating said shoe-positioning gages.

8. A machine for applying pressure to shoe bottoms having, in combination, a sole-engaging pad, a shoe-engaging device movable into position over the pad and constructed and arranged to cooperate with the pad in applying pressure to a shoe and sole on the pad, a pair of pivotally mounted gages for positioning the heel-end portion of a sole on the pad, a second pair of pivotally mounted gages for positioning the rear end of a shoe relatively to the sole, and connections operated by the movement of said shoe-engaging device into position over the pad for moving said shoe-positioning gages into operative position.

9. A pad box for use in applying pressure to shoe bottoms provided with a sole-receiving pad, a bracket mounted on the pad box and arranged for adjustment heightwise of the pad, a pair of sole-positioning fingers carried by the bracket, a separate pair of shoe-positioning fingers also carried by the bracket, and means for adjusting the bracket heightwise of the pad.

10. A pad box for use in applying pressure to shoe bottoms provided with a sole-receiving pad, a pair of gage fingers for positioning a sole relatively to the pad, said fingers being fulcrumed on the pad box and arranged for equal and opposite rocking movements about axes alined with each other transversely of the pad, a slide movable transversely of the pad for effecting rocking movement of the fingers to position the sole on the pad, a second pair of fingers for positioning a shoe relatively to the sole, said last-named fingers being also fulcrumed on the pad box and arranged

for equal and opposite rocking movement about axes alined with each other transversely of the pad, and means for effecting rocking movement of said last-named fingers to position the shoe relatively to the sole.

11. A pad box for use in applying pressure to shoe bottoms provided with a sole-receiving pad, a bracket mounted on the pad box and arranged for adjustment heightwise of the pad, a carrier member pivotally mounted on the bracket and arranged for movement lengthwise of the pad, sole and shoe-positioning gages carried by the carrier member and constructed and arranged to position a sole and shoe relatively to each other on the pad, means for adjusting the bracket heightwise of the pad, and means for moving the carrier member lengthwise of the bracket.

12. A pad box for use in applying pressure to shoe bottoms provided with a sole-receiving pad, a bracket mounted on the pad box and arranged for adjustment heightwise of the pad, a carrier member pivotally mounted on the bracket and arranged for movement lengthwise of the pad, a pair of sole-positioning gages pivoted on the carrier member for rocking movement transversely of the pad, a pair of shoe-positioning gages also pivoted on the carrier member and arranged for rocking movement transversely of the pad, connections between the gages of each pair for limiting their rocking movement to equal amounts in opposite directions, and a cam for adjusting the bracket heightwise of the pad.

13. A pad box for use in applying pressure to shoe bottoms provided with a sole-receiving pad, a bracket mounted on the pad box, a carrier member pivotally mounted on said bracket, a sole and shoe-positioning gages carried by said carrier member, the ends of said gages being located above the upper surface of the pad, an abutment on the bracket arranged to support the carrier member rearwardly of its pivot, a roll on the carrier member for engaging said abutment, and means for adjusting said abutment heightwise of the pad to rock the carrier member about its pivot and thereby cause the gages to approach or move away from the upper surface of the pad.

14. A pad box for use in applying pressure to shoe bottoms provided with a sole-receiving pad, a bracket mounted on the pad box, a carrier member pivotally supported on said bracket, separate pairs of sole and shoe gages carried by said carrier member, the gages of each pair being fulcrumed for rocking movement in equal amounts in opposite directions transversely of the pad, an adjustable abutment carried by the bracket and arranged to support the carrier member rearwardly of its pivot, a roll on the carrier member for engaging said abutment, a spring for holding said roll against said abutment, and means for adjusting said abutment heightwise of the pad to rock the carrier member about its pivot and thereby move the gages nearer to or farther away from the sole-engaging surface of the pad.

15. A pad box for use in applying pressure to shoe bottoms provided with a sole-receiving pad, a bracket mounted on an end of the pad box, a carrier member pivoted on said bracket, sole and shoe-positioning fingers carried by said carrier member and arranged for rocking movement about axes alined with each other transversely of the pad, the outer ends of the sole-positioning fingers being normally located in close proximity to the upper surface of the pad, means for rocking said fingers about their respective axes toward and away from operative position, a roll on one

- end of the carrier member, an abutment on the bracket for engaging the roll and supporting the carrier member normally in a substantially horizontal position, a spring for holding said roll 5 in contact with said abutment, and means for adjusting the abutment heightwise to rock the carrier member about its pivot and thereby cause the sole-positioning fingers to approach or move away from the upper surface of the pad.
16. A pad box for use in applying pressure to shoe bottoms provided with a sole-receiving pad, a bracket mounted on the pad box and arranged for adjustment heightwise of the pad, a supporting lever fulcrumed on said bracket and arranged for rocking movement lengthwise of the pad, a carrier member pivotally supported by said lever, said carrier member being supported normally in a substantially horizontal position and being adjusted lengthwise of the pad by rocking movement of the supporting lever, sole and shoe-positioning gages carried by said carrier member and constructed and arranged to position a sole and shoe relatively to each other on the pad, and means on the bracket for moving said carrier member out of a horizontal position and returning it to such position during its adjustment lengthwise of the pad.
17. A pad box for use in applying pressure to shoe bottoms provided with a sole-receiving pad, a bracket mounted on the pad box, a supporting lever fulcrumed on said bracket, a carrier member pivotally mounted on said supporting lever and adjustable lengthwise of the pad by pivotal movement of said lever, sole and shoe-positioning gages carried by the carrier member and constructed and arranged to position a sole and shoe relatively to each other on the pad, and means on the bracket for maintaining the carrier member normally in a substantially horizontal position to locate the sole gages close to the upper surface of the pad, said means comprising an abutment engaging the carrier member rearwardly of its pivot and constructed and arranged to cause the forward end of the carrier member to rise and then to return to a substantially horizontal position during the lengthwise movement of said member, thereby lifting the positioning gages away from the upper surface of the pad and returning them to their original positions after said movement has been completed.
18. A pad box for use in applying pressure to shoe bottoms provided with a sole-receiving pad, a bracket mounted on the pad box and arranged for adjustment heightwise of the pad, a cam for adjusting said bracket, an upwardly extending lever pivotally mounted on the bracket and arranged for rocking movement lengthwise of the pad, a carrier member pivoted on the upper end of said lever, an adjustable abutment for supporting the carrier member rearwardly of its pivot to maintain said member normally in a substantially horizontal plane, sole and shoe-positioning gages carried by the carrier member and constructed and arranged to position a sole and shoe relatively to each other on the pad, and means for adjusting the abutment heightwise to rock the carrier member about its pivot and thereby raise or lower the gages relatively to the upper surface of the pad.
19. A pad box for use in applying pressure to shoe bottoms provided with a sole-receiving pad, a bracket mounted on the pad box and arranged for adjustment heightwise of the pad, means 75 for adjusting said bracket, a lever fulcrumed on the bracket and arranged for rocking movement lengthwise of the pad, a carrier member pivotally supported by the lever, said carrier member being supported normally in a substantially horizontal position to locate the sole gages close to the upper surface of the pad, sole and shoe-positioning gages carried by the carrier member and constructed and arranged to position a sole and shoe relatively to each other on the pad, and means for adjusting the abutment heightwise to rock the carrier member about its pivot and thereby raise or lower the gages relatively to the upper surface of the pad.
20. A pad box for use in applying pressure to shoe bottoms provided with a sole-receiving pad, a bracket mounted on the pad box, a lever fulcrumed on said bracket, a carrier member pivotally supported on one end of said lever, sole and shoe-positioning gages carried by said carrier member, said sole gages being located close to the upper surface of the pad, and means for effecting a quick adjustment of the carrier member relatively to the end of the supporting lever to vary the position of the sole gages relatively to the upper surface of the pad.
21. A pad box for use in applying pressure to shoe bottoms provided with a sole-receiving pad, a bracket mounted on the pad box, a lever fulcrumed on said bracket and arranged for rocking movement lengthwise of the pad, a carrier member pivoted on said lever, said carrier member being adjustable lengthwise of the pad by rocking movement of the lever, means for engaging the carrier member rearwardly of its pivot to support said member normally in a substantially horizontal position, sole and shoe-positioning gages carried by said carrier member and constructed and arranged to position a sole and shoe relatively to each other on the pad, and eccentric means for obtaining a quick adjustment of the carrier member relatively to the lever to move said member out of said horizontal position and thereby raise or lower the positioning gages relatively to the upper surface of the pad.
22. A pad box for use in applying pressure to shoe bottoms provided with a sole-receiving pad, a bracket mounted on the pad box and arranged for adjustment heightwise of the pad, a cam for adjusting said bracket heightwise, a substantially vertical lever fulcrumed on said bracket and arranged for rocking movement lengthwise of the pad, means for limiting the rocking movement of said lever, a carrier member pivotally supported on the upper end of said lever, an abutment for engaging the carrier member rearwardly of its pivot and supporting said member normally in a substantially horizontal position, sole and shoe-positioning gages carried by the carrier member and constructed and arranged to position a sole and shoe relatively to each other on the pad, means for effecting a heightwise adjustment of the abutment to position the sole-positioning gages relatively to the upper surface of the pad, and means for obtaining a quick adjustment of the carrier member relatively to the end of the supporting lever to move said member out of a substantially horizontal position and thereby

raise or lower the positioning gages relatively to the upper surface of the pad.

23. A pad for use in applying pressure to shoe bottoms and provided with a pair of gage fingers
5 for positioning an end portion of a shoe relatively to the pad, said fingers being fulcrumed for rocking movement about axes alined with each other transversely of the pad and being provided with means limiting the rocking move-
10 ment of the fingers to equal but opposite move-
ment about their fulcrums, and a slide movable transversely of the pad in the vicinity of the ful-
crums of the fingers, one of said fingers having a projection cooperating with a cam surface of
15 the slide whereby movement of the slide trans-
versely of the pad will rock the fingers toward or from operative position.

24. A pad for use in applying pressure to shoe bottoms and provided with a pair of gage fingers for positioning an end portion of a shoe relatively to the pad, said fingers being fulcrumed for rocking movement about axes alined with each other transversely of the pad and being provided with intermeshing gear segments concentric with the fulcrums of the fingers, and a slide movable transversely of the pad in the vicinity of the fulcrums of the fingers, one of said fingers having a projection cooperating with a cam surface of the slide whereby movement of the slide transversely of the pad will rock the fingers toward or from operative position.

25.

30.

25. A pad for use in applying pressure to shoe bottoms and provided with a pair of gage fingers for positioning an end portion of a shoe relatively to the pad, said fingers being fulcrumed for rocking movement about parallel axes alined with each other transversely of the pad and being provided with intermeshing gear segments concentric with the fulcrums of the fingers, and a slide movable transversely of the pad in the vicinity of the fulcrums of the fingers, one of said fingers carrying a roll located in a cam slot of the slide whereby movement of the slide transversely of the pad will rock the fingers toward or from operative position, the inclination of the cam slot and the direction of movement of the slide being such as to lock the fingers against movement toward and from each other under the influence of forces applied to the fingers other than by movement of the slide.

26. A pad for use in applying pressure to shoe bottoms and provided with a pair of gage fingers for positioning an end portion of a sole relatively to the pad, said fingers being fulcrumed for rocking movement about parallel axes alined with each other transversely of the pad and extending heightwise of a shoe on the pad, said fingers being provided with means for limiting rocking movement of the fingers to equal but opposite movement about their fulcrums, a slide movable transversely of the pad in the vicinity of the fulcrums of the gage fingers, one of said fingers having a projection cooperating with a cam surface of the slide whereby movement of the slide transversely of the pad will rock the fingers toward or from operative position, a second pair of gage fingers for positioning an end portion of a shoe relatively to the sole on the pad, said last-named fingers being fulcrumed for rocking movement about axes parallel to and adjacent to the fulcrums of the sole-engaging fingers, means limiting rocking movement of the shoe-engaging fingers to equal but opposite movement about their fulcrums, and means for rocking the shoe-

engaging fingers into and out of operative position.

27. A pad for use in applying pressure to shoe bottoms and provided with a pair of gage fingers for positioning an end portion of a sole relatively to the pad, said fingers being fulcrumed for rocking movement about axes alined with each other transversely of the pad and extending heightwise of a shoe on the pad and being provided with means limiting rocking movement of the fingers to equal but opposite movement about their fulcrums, a second pair of gage fingers for positioning an end portion of a shoe relatively to the sole on the pad, said fingers being fulcrumed for rocking movement about axes respectively substantially parallel to and normally coincident with the fulcrums of the sole-engaging fingers, and means limiting rocking movement of the shoe-engaging fingers to equal but opposite movement about their fulcrums, said shoe-engaging fingers being fulcrumed to a slide mounted for adjustment transversely of the pad so that the fulcrums of the shoe-engaging fingers may be adjusted relatively to the fulcrums of the sole-engaging fingers to compensate for a lack of symmetry in the portion of the shoe engaged by the shoe-engaging fingers.

28. A pad for use in applying pressure to shoe bottoms and provided with a pair of gage fingers for positioning an end portion of a sole relatively to the pad, said fingers being fulcrumed for rocking movement about parallel axes alined with each other transversely of the pad and extending heightwise of a shoe on the pad, said fingers being provided with means for limiting rocking movement of the fingers to equal but opposite movement about their fulcrums, a slide movable transversely of the pad in the vicinity of the fulcrums of the gage fingers, connections between the fingers and the slide constructed and arranged so that movement of the slide transversely of the pad will rock the fingers toward or from operative position, a second pair of gage fingers for positioning an end portion of a shoe relatively to the sole on the pad, said last-named fingers being fulcrumed for rocking movement about axes parallel to and adjacent to the fulcrums of the sole-engaging fingers, means limiting rocking movement of the shoe-engaging fingers to equal but opposite movement about their fulcrums, a slide movable transversely of the pad in the vicinity of the previously-mentioned slide, and connections between the shoe engaging fingers and the last-named slide constructed and arranged so that movement of that slide transversely of the pad will rock the shoe-engaging fingers toward or from operative position.

29. A pad for use in applying pressure to shoe bottoms and provided with a pair of gage fingers for positioning an end portion of a sole relatively to the pad, said fingers being fulcrumed for rocking movement about parallel axes alined with each other transversely of the pad and extending heightwise of a shoe on the pad, said fingers being provided with means for limiting rocking movement of the fingers to equal but opposite movement about their fulcrums, a slide movable transversely of the pad in the vicinity of the fulcrums of the gage fingers, one of said fingers having a projection cooperating with a cam surface of the slide whereby movement of the slide transversely of the pad will rock the fingers toward or from operative position, a second pair of gage fingers for positioning an end portion of a shoe relatively to the sole on the pad. 60 65 70 75

versely of the pad will rock the fingers into and out of operative position, and means for adjusting said abutment heightwise of the pad to position the fingers in close proximity to the upper surface of the pad.

35. A pad box for use in applying pressure to shoe bottoms having, in combination, a sole and shoe-receiving pad, a bracket mounted on the pad box and arranged for adjustment heightwise of the pad, a cam for adjusting said bracket heightwise, a lever fulcrumed on said bracket and arranged for rocking movement lengthwise of the pad, a carrier member pivotally supported by said lever, said carrier member being adjustable lengthwise of the pad by rocking movement of the supporting lever, an abutment on the bracket for tilting the carrier member during its lengthwise adjustment and for returning it to its original position at the end of such adjustment, separate pairs of sole and shoe-positioning gages carried by the carrier member and arranged to position a sole and shoe relatively to each other on the pad, the gages of each pair being fulcrumed for rocking movement about axes alined with each other transversely of the pad and being provided with means for limiting their rocking movement to equal amounts in opposite directions, a slide associated with each pair of gages and movable transversely of the pad in the vicinity of the fulcrums of the gages, one gage of each pair having a projection cooperating with a cam surface on its corresponding slide whereby movement of said slide transversely of the pad will rock the gages of that pair toward or away from operative position, and means for effecting a heightwise adjustment of the abutment to move the carrier member about its pivot and thereby to raise or lower the ends of the gages relatively to the upper surface of the pad.
36. A pad box for use in applying pressure to shoe bottoms provided with a sole-receiving pad, a bracket mounted on an end of the pad box and arranged for adjustment heightwise of the pad, a cam for adjusting said bracket heightwise, a carrier member pivoted normally in a substantially horizontal position on said bracket, sole and shoe-positioning fingers carried by said carrier member and arranged for rocking movement about axes alined with each other transversely of the pad, slides movable transversely of the pad for rocking said fingers about their respective axes toward and away from operative position, a roll on the rear end of the carrier member, an abutment on the bracket for engaging the roll and supporting the carrier member normally in a substantially horizontal position, a spring for holding said roll in contact with the abutment, and means for adjusting the abutment height-

wise to move the carrier member about its pivot and thereby to cause the positioning fingers to approach or move away from the upper surface of the pad.

37. A pad box for use in applying pressure to shoe bottoms provided with a sole-receiving pad, a pair of sole-positioning fingers mounted on the pad box, a separate pair of shoe-positioning fingers also mounted on the pad box above the sole-positioning fingers, elongated members on the ends of the shoe-positioning fingers, the lower edges of said members being normally located in close proximity to the ends of the sole-positioning fingers, and connections between the elongated members and the shoe-positioning fingers whereby the positions of said members may be reversed to create additional space between the ends of the shoe-positioning fingers and the ends of the sole-positioning fingers.

38. A pad box for use in applying pressure to shoe bottoms provided with a sole-receiving pad, a pair of sole-positioning fingers mounted on the pad box and having their sole-engaging ends located in close proximity to the upper surface of the pad, a pair of shoe-positioning fingers mounted on the pad box above the sole-positioning fingers, said shoe-positioning fingers having slots in their outer ends, elongated plates mounted in said slots, the lower ends of said plates extending close to the ends of the corresponding sole-engaging fingers, stems on the plates for holding them in position on the shoe-engaging fingers, and springs surrounding said stems, said springs permitting removal of the plates from the slots and rotation of the plates into reversed positions relatively to the ends of the shoe-engaging fingers, thereby substantially increasing the space between the ends of the sole-positioning fingers and the shoe-positioning fingers.

39. A pad box for use in applying pressure to shoe bottoms provided with a sole-receiving pad, a bracket mounted on the pad box and arranged for adjustment heightwise of the pad, a pair of sole-positioning fingers mounted on the bracket, a separate pair of shoe-positioning fingers also mounted on the bracket above the sole-positioning fingers, said shoe-positioning fingers having downwardly extending plates movably secured to their shoe-engaging ends, means for adjusting the bracket heightwise to position the fingers for shoes having heels of different heights, and means for reversing the positions of the plates on the shoe-engaging fingers thereby increasing the space between the ends of the sole-positioning fingers and the ends of the shoe-positioning fingers to adapt the fingers for operating upon shoes having relatively high heels.

ROBERT N. SANDBERG.
